APPARATUS FOR SPONGING AND REFINISHING CLOTH.

1,086,086.

Specification of Letters Patent.

Patented Feb. 3, 1914.

Application filed April 19, 1912. Serial No. 691,937.

To all whom it may concern:

Be it known that I, EDGAR F. RUMMLER, a citizen of the United States, residing at Elmhurst, in the borough of Queens, city of New York, county of Queens, and State of New York, have invented certain new and useful Improvements in Apparatus for Sponging and Refinishing Cloth, of which the following is a specification, reference being had therein to the accompanying drawings, which form a part thereof.

My invention relates to an apparatus for sponging and finishing cloth in the piece, and more particularly to an apparatus adapted for use in shrinking cloth and in refinishing it preparatory to cutting it for the manufacture of clothing.

Heretofore it has been the general practice in sponging and refinishing cloth to first wet or dampen the cloth in the piece and thereafter lay sections of the piece upon a table having a metal top heated by means of steam coils, for a length of time sufficient to remove all of the moisture from the cloth. After this section had been dried to the desired extent, it was removed from the table and the next section of equal length laid thereon, this operation being repeated until the entire length of the piece had been dried and shrunk. To insure uniformity in the conditioning of the entire piece, it was necessary that the length of time during which each section remained on the table should be the same as every other, and constant attention was required to avoid such a variance of time as would result in improperly or unevenly shrunken sections of the piece. As each section was removed from the table, it was permitted to lie in folds until the entire piece was shrunk, and after this it was necessary to refinish the cloth in a separate machine before cutting up for garments. If in shrinking any section were allowed to remain too long on the table, this section would be damaged in a degree which would make it practically worthless.

To obviate the conditions in the method above referred to, it has been endeavored to dry an entire piece of cloth simultaneously by looping it within a drying box, the cloth after being shrunk, being removed from the box and refinished. This practice, however, is not generally followed, the drying table being more generally used.

With these conditions in mind, the main

object of my invention is to provide an apparatus for sponging and refinishing cloth by a continuous treatment, whereby succeeding portions of a previously dampened piece of cloth will be progressively subjected to the action of a dry heat for a uniform length of time so as to gradually and uniformly shrink every portion of the piece to the maximum extent, and immediately after the shrinking process upon each portion of the cloth is completed, and while it is still warm, subjecting it to such treatment as will automatically refinish the cloth without the necessity for further handling.

A further object is to provide such an apparatus wherein a substantially continuously moved piece of cloth will have the moisture gradually removed from succeeding portions thereof with the progressive movement of the cloth through an elongated heating box, and wherein the cloth will be subjected to such treatment at an interval when the moisture has been entirely removed therefrom, as will result in a refinishing of each section of the piece as it is completely shrunk and before it has been permitted to cool.

A still further object is to provide an apparatus by means of which a piece of cloth may be gradually fed across a heating box without contact with the heating means, and in a manner to permit that contraction of the cloth incidental to the shrinkage occurring during the progress of the cloth.

A still further object is to provide an apparatus of this character wherein the piece of cloth immediately upon leaving the heating box will be tightly rewound while still heated.

A still further object is to provide an apparatus of this character wherein the cloth will be conveyed across the heating box by a conveyer which will not exert any substantial stress upon the cloth thereupon, thus leaving the cloth free to contract during the shrinking operation while passing over the heating box.

A still further object is to provide an apparatus which will operate continuously in conveying the cloth across the heating box at a speed which will cause the gradual evaporation of all of the moisture therein and the completion of the shrinking of the cloth substantially simultaneously with the cloth leaving the box.

A still further object is to provide an apparatus of this character wherein the speed of travel of the conveyer may be varied to adapt the apparatus to cloths of different 5 weights.

A still further object is to provide an apparatus of this character wherein the conveyer and the rewinding mechanism will bear such relation to each other as to insure 10 the application of sufficient pressure to the heated cloth as it is being rewound, to result in the refinishing of the cloth before it leaves the apparatus.

A still further object is to provide in an 15 apparatus of this character, a conveyer mechanism having sections thereof roughened so as to cause the end of the cloth to be gripped thereby to initiate the feed thereof from the dampened roll.

20 A still further object is to provide an apparatus of this character wherein a flexible conveyer may be used in a manner to permit the cloth thereon to assume any form, and prevent such conditions as would interfere 25 with the free shrinking of the cloth. And a still further object is to provide an apparatus of this character wherein after the roll of dampened cloth has been mounted therein and the machine has been set in operation, 30 the machine itself will operate automatically in a manner to shrink the entire roll and refinish the same without requiring any further attention beyond the removal of the shrunken cloth.

35 The invention consists in the novel method or art of sponging and refinishing cloth, and the novel features of construction and combination of parts of an apparatus for practising said method or art, all as 40 hereinafter set forth and described, and more particularly pointed out in the claims hereto appended.

Referring to the drawings:—Figure 1 is 45 a longitudinal section of an apparatus used in practising my improved method or art; and Fig. 2 is a plan view thereof with sections broken away to disclose the relation of parts.

Like letters refer to like parts in both of 50 the said views.

In the practice of my invention, I first dampen a piece of cloth in any desired manner so as to impart to it a degree of saturation uniform throughout, which cloth after 55 being so dampened is preferably rolled to prevent evaporation and afford greater convenience in handling. I then take the end of the roll of cloth and pass it and succeeding portions of the cloth progressively and uniformly 60 directionally over an elongated source of dry heat in a manner to gradually and progressively remove the moisture from the cloth while it is in motion. In this manner each portion of the cloth is treated 65 under exactly the same conditions, and the

shrinking process is completed only as each portion passes from the effective range of the dry heat. The cloth is moved very slowly to afford sufficient time to accomplish its thorough drying and resultant 70 shrinkage, and the drying and shrinking are gradual as to every portion of the piece, each portion being subjected to the action of the heat only for a period sufficient to remove all of the moisture and thus secure the 75 maximum shrinkage. As the cloth is removed from the effective range of the dry heat and while it is still warm therefrom, I rewind it in a compact roll, subjecting it to pressure as it is being rewound, and allow 80 the cloth to cool while it is in the roll. In actual practice, I have demonstrated that by so treating the cloth, the nap is laid sufficiently to give to the cloth a satisfactory finish so that when cooled, it may be 85 removed directly to the cutting tables. I thus eliminate the necessity for refinishing by methods now in use, and not only economize in the cost of preparing the cloth for the cutting table, but secure, with a minimum expenditure of time and labor, a satisfactory finish in the cloth.

The apparatus shown in the accompanying drawings consists of an elongated heating box *a*, having therein a series of steam 95 coils *b*, through which is caused to flow steam under low pressure so as to avoid the presence of excessively high temperatures. This box is closed upon the bottom and at the sides. At the opposite ends of the 100 box *a* are the frames *c d*, the former of which is provided with a standard *e* in which is adapted to be detachably mounted the trunnions of a shaft *f* upon which a previously semi-saturated or dampened 105 piece of cloth is rolled. Also carried by the frame *c* are a plurality of idler rollers *g g'* which serve as guides for a continuous flexible conveyer *h* which partially closes the top of the box *a* and in addition to carrying the 110 cloth slowly across the said box, acts as a shield to prevent possible contact of the cloth with the coils *b*.

The conveyer *h* is driven at very low speed 115 by means of a roughened driving roller *i* mounted upon the frame *d*, which roller is driven through a suitable speed reducing mechanism from the electric motor *j*. With cloths differing in weight, it is necessary to vary the speed of travel of the conveyer in 120 order to afford that period of time during which the cloth is traversing above the heating box, necessary to remove all of the moisture from the cloth and to give the maximum shrinkage thereto. In the apparatus 125 shown in the drawings, the speed controlling mechanism for the driving power of the conveyer *h* is an ordinary rheostat *k* by means of which the speed of the motor *j* may be varied. While an electric motor 130

drive with rheostat control is desirable as being good shop practice, I do not intend to limit myself to any particular form of power.

5 The conveyer belt *h* passes about the driving roller *i* and is guided in its movement beneath the box *a* by suitable idler rollers *l*. To increase the effective utilization of the heat from the coils *b* in drying the cloth, I 10 use a flexible fabric for the conveyer belt *h*, which material has the advantage of absorbing moisture from the cloth, thus permitting the moisture in the cloth to radiate in all directions, and of yielding transversely with 15 the cloth as it shrinks, if the adhesion of the cloth to the conveyer is sufficiently great to prevent such movement of the cloth independently of said belt. In making the conveyer belt, I preferably select a smooth, 20 hard textile fabric to minimize such adhesion, and provide sections of softer material as *h'* adapted to receive the end of the roll of cloth and have sufficient adhesion thereto to initiate the feed of the cloth with 25 the belt.

Extending across the box *a* is a plurality of narrow supports *a'* adapted to prevent engagement of the belt *h* with the pipes *b*.

To keep the conveyer belt *h* as flat as 30 possible, I provide the driving roller *i* with oppositely pitched stretching ribs *i'* as shown, these ribs serving to remove any wrinkles should the cloth shrink transversely and carry the belt with it.

35 Arranged between the driving rollers *i* and the box *a* are standards *m* having elongated forked upper ends adapted to receive the trunnions of a weighted rewinding roller *n*, and mounted in the standards *m* below said forks is a presser roller *o* oppositely disposed as to, and adapted to sustain the lead of, the rewinding roller *n* and the cloth as it is being rewound thereon. The conveyer *h* passes between the roller 40 *n* *o* and thence upwardly to the driving roller *i* which occupies a higher plane than said roller *o*.

The standards *e* and *m* are spaced considerable distance apart, the box *a* occupying substantially the entire distance between these parts. The conveyer belt *h* is of a 50 width to substantially close the entire top of the box *a* thus constituting a traveling top therefor adapted to receive the cloth and convey it along the length of the box.

The cloth to be dried, shrunk and refinished is indicated at *p*.

60 The operation of the herein described apparatus is substantially as follows:—The roll of cloth *p* is first dampened in any desired manner and wound upon the roller *f*, and the trunnions of this roller are mounted in the bearings in the standards *e*. The circuit to the motor is then closed, rotating 65 the shaft *i* at low speed and imparting a

continuous movement to the absorbent textile conveyer belt *h* above the coils *b* in the box *a*. The end of the roll of cloth *p* is first brought into engagement with the belt *h* and if the adhesion between the belt and this end is not sufficient to hold the cloth thereon, slippage will occur between the belt and the cloth until a section *h'* of roughened material of the belt *h* engages the cloth whereupon the cloth will be fed from its roll by, and simultaneously with, the belt *h* upon which it lies. As each portion of the cloth progresses along the box *a* it will be gradually dried and shrunk, the different portions of the cloth being progressively brought to the desired dry state. The supports *a'* will prevent the sagging of the belt at any point in a manner to permit it to contact with the steam coils *b*, thus causing the drying of the cloth through the 70 heat radiated from said coils. The absorbent nature of the belt *h* will cause it to take up some of the moisture of the cloth, and this moisture will be driven from the belt by the dry heat, thus causing the moisture to radiate in all directions and not limiting such evaporation to the upper surface of the cloth. As the cloth progresses along the length of the box *a*, it will shrink laterally, and if any adhesion occurs between the cloth and the belt which prevents slippage of the former upon the latter, the belt itself is free to give laterally so that there is always a free shrinkage of the cloth. The speed of the motor *j* is so regulated as 75 to cause all of the moisture to be driven from the cloth as it approaches the standards *m* and its weighted roller. As the dry cloth while still heated, passes between the rollers *n* *o*, the upward tendency of the belt *h* will press the cloth firmly against the roller *n*, the weight of which will exert sufficient pressure to practically iron the cloth as it is rolled upon the roller *n*. The roller *n* is free to move upwardly in the standards *m* as the roll increases in diameter. In 80 starting the rewinding operation, it is merely necessary to wrap the forward end of the cloth about the roller *n*. This roller also serves to keep the belt *h* fairly taut as it passes over the heating box. As the belt *h* passes over the roller *i*, any longitudinal wrinkles therein, due to the transverse movement of the cloth in shrinking, will be removed by the ribs *i'* on this roller, which 85 ribs, together with the roughened surface of this roller, will serve to afford the proper grip to insure the continuous feeding movement of the belt.

It being merely necessary to start the 90 feeding movement of the cloth with the belt, and the duration of the time during which the cloth is subjected to the action of the heat from the box *a* being controlled by the speed of the belt *h*, the machine requires 95

no attention after the feeding movement of the cloth has once been started. Furthermore, as each portion of the cloth is progressively treated in the same manner as the preceding portion, the condition of the entire piece will be uniform throughout.

The rewinding roller *n* being arranged without the effective range of the heat box *a*, in case the operator is absent when the shrinking of one piece is completed, the cloth will remain upon this roller *n* and will cool without possibility of injury to the cloth by reason of this neglect.

I have found in practice, that the mere rewinding of the cloth in the manner described, immediately after it has been shrunk and while it is still heated, accomplishes a highly satisfactory refinishing of the goods so that they may be removed directly from the machine to the cutting tables without further treatment. Experience has also demonstrated that by continuously and slowly moving the dampened cloth through the heat from the heating box, and in one direction, the maximum shrinkage of the cloth may be secured, and there is no likelihood of injury to the cloth from the application of heat thereto for too great a length of time.

It is not my intention to limit the invention to the precise details of construction of the apparatus herein shown and described, it being apparent that such may be varied without departing from the spirit and scope of the invention.

Having described my invention, what I claim as new and desire to have protected by Letters Patent, is:—

1. An apparatus for sponging and refinishing cloth embodying therein a support for a roll of dampened cloth, an elongated heating box extending from adjacent to said support, an endless belt passing over said heating box, said belt being adapted to support the cloth and convey it through the heat rays radiating from said box, and means imparting a substantially continuous, slow movement to said belt.

2. An apparatus for sponging and refinishing cloth embodying therein a support for a roll of dampened cloth, an elongated heating box extending from adjacent to said support, an endless belt of flexible material passing over said heating box, said belt being adapted to support the cloth and convey it through the heat rays radiating from said box, supports for said belt carried by said box, whereby the sagging of said belt is prevented, and means imparting a substantially continuous, slow movement to said belt.

3. An apparatus for sponging and refinishing cloth embodying therein a support for a roll of dampened cloth, an elongated heating box extending from adjacent to said support, an endless belt passing over said

heating box, said belt being adapted to support the cloth and convey it through the heat rays radiating from said box, means imparting a substantially continuous, slow movement to said belt, and means whereby the speed of the feeding movement of said belt may be varied.

4. An apparatus for sponging and refinishing cloth embodying therein a support for a roll of dampened cloth, an elongated heating box extending from adjacent to said support, an endless belt passing over said heating box, said belt being adapted to support the cloth and convey it through the heat rays radiating from said box, said belt being composed of a material to which the cloth will not readily adhere whereby the cloth will be moved over said heating box and will be permitted to shrink freely, and means imparting a substantially continuous, slow movement to said belt.

5. An apparatus for sponging and refinishing cloth embodying therein a support for a roll of dampened cloth, an elongated heating box extending from adjacent to said support, an endless belt passing over said heating box, said belt being adapted to support the cloth and convey it through the heat rays radiating from said box, said belt being composed of a material to which the cloth will not readily adhere whereby the cloth will be moved over said heating box and will be permitted to shrink freely, and having a strip of material to which the cloth will adhere adapted to engage the free end of the roll of cloth, and means imparting a substantially continuous, slow movement to said belt.

6. An apparatus for sponging and refinishing cloth embodying therein a support for a roll of dampened cloth, an elongated heating box extending from adjacent to said support, an endless belt passing over said heating box, said belt being adapted to support the cloth and convey it through the heat rays radiating from said box, means imparting a substantially continuous, slow movement to said belt, and a rewinding mechanism adjacent to the end of said box opposite said support, whereby the cloth upon leaving the box will be tightly wound.

7. An apparatus for sponging and refinishing cloth embodying therein a support for a roll of dampened cloth, an elongated heating box extending from adjacent to said support, an endless belt of flexible material passing over said heating box, and means imparting a substantially continuous, slow movement to said belt, including therein a driving roller having a plurality of oppositely pitched ribs thereon whereby said belt will be stretched laterally after leaving the heating box.

8. An apparatus for sponging and refinishing cloth embodying therein a support for

a roll of dampened cloth, an elongated heating box extending from adjacent to said support, an endless belt passing over said heating box, said belt being adapted to support the cloth and convey it through the heat rays radiating from said box, a rewinding mechanism adjacent to the end of said box opposite said support, comprising a fixed roller and a vertically movable weighted roller, between which said belt passes, a driving roller disposed above and beyond said last named rollers, whereby the cloth being rewound upon said weighted roller will be subjected to pressure from the weight of said

roller and from the upward stress upon said belt, and means for substantially continuously rotating said driving roller to impart a substantially continuous movement to said belt.

In witness whereof, I have hereto affixed my signature, in the presence of two subscribing witnesses, this 11th day of April, 1912.
